ELECTRIC RELEASE MECHANISM FOR
KNITTING MACHINESDavid Wachsman, Brooklyn, N. Y., assignor to
Wachsman Sons', Inc., a corporation of New
York

Application April 6, 1940, Serial No. 328,251

1 Claim. (Cl. 66—163)

This invention relates to electric release mechanisms for knitting machines of the type disclosed in the U. S. Patent 1,845,455, February 16, 1932. The object of the invention is to provide an improved type of such release mechanism for actuating the stop handle of the driving unit of the machine when a thread breaks or runs out. One object is to provide a device in which the number of parts are reduced to a minimum together with certain novel features of design and construction providing a mechanism easy and inexpensive to manufacture, easy to assemble and install and having certain features of construction facilitating easy adaptation to knitting machines stop mechanisms. In the accompanying drawing illustrating the invention—

Fig. 1 is a view in elevation of the release mechanism which is contained in a box the cover of which is removed.

Fig. 2 is a longitudinal sectional view through the box on the line 2—2 of Fig. 1 with some details left out.

Fig. 3 is a transverse sectional view on the line 3—3 of Fig. 2 with parts omitted.

Fig. 4 is a diagram.

Referring first to Fig. 4 the numeral 10 indicates conventionally a stop handle of a driving unit in a knitting machine. When the handle is swung on its pivot 11 the knitting machine stops. The operation is similar to that of shifting a belt pulley in other machinery. In knitting machines the operation of the stop handle is controlled by the thread. That is, when the thread breaks or runs out the handle 10 is to be operated to stop the machine. The controlling mechanism is in the form of a switch which is normally held in circuit open position by the thread. Such switches are called end detectors or knot detectors or stop motions in the art. In Fig. 4 it will be seen that the thread 12 runs over two guides 13, 13 and that a detector 14 rests upon the thread. The detector 14 is merely a switch arm which, when not supported by the thread, moves down by any suitable means and contacts a switch plate 15 which is grounded. The detector is connected to a battery 16. This in turn is connected to an electromagnet 17. The other end of the coil is connected to a spring contact 18 which is grounded. It will therefore be seen that so long as the switch or detector 14 is supported by the thread the circuit is open and the electromagnet cannot attract its armature lever 19.

The latter acts to hold a locking lever 20 in position to lock a plunger 21 against movement

by the action of a plunger spring 22. The plunger is adapted to move the stop handle 10 as shown. If now the detector switch is closed because the thread breaks or runs out, the circuit is closed, the magnet is energized, the armature lever 19 is actuated to release the locking lever 20 which falls down by gravity thereby releasing the plunger 21. The latter is then moved by the plunger spring 22 to throw the stop handle 10 to stop the machine and the circuit is then immediately open at the spring contact 18. Thus only for a moment is the circuit closed. This is the usual procedure to avoid accidents due to shocks. The detector switch and other parts in Fig. 4 are shown wholly conventional. The foregoing is a brief description of the operation of a typical electric stop mechanism for knitting machines. This invention is concerned with the construction and arrangement of those parts of the mechanism whereby the plunger is held, operated and again set for the next operation.

Referring now to Figs. 1 to 3 the plunger 21 is slidably supported in two cut outs or slots 24, 24 in the box 25 which contains and supports the several parts. The box has a cover 26 with overhanging lips 27, 27 extending down over the said slots to keep the plunger therein so it cannot jump out or tip. The plunger carries a hook 28 which engages a nose 29 on the locking lever 20. The latter is relatively very long and pivoted at 30. The long arm 31 of the lever 20 tends to fall down to the bottom of the box 25 by gravity but is normally prevented therefrom by the armature lever 19 which has a lip 32 which engages under a hook 33 on the locking lever.

The armature lever is pivoted at 34 in the box and is urged away from the magnet 17, 17 by a spring 35. A stop 36 positions the armature lever with relation to the magnet. Current is supplied to the latter by way of a circuit terminal 37 which is also connected to the aforesaid spring contact 18. In normal position when the magnet is not energized the locking lever 20 engages the spring contact 18. The lever is preferably of brass or other conducting material so the circuit at 18 is grounded on the box via the lever 20. A pin 40 is provided for manual operation of the armature lever 19 to test the device by pushing the pin inward whereby to release the locking lever.

In operation the normal positions of the parts are as shown in the drawing. The operator has pushed the plunger 21 to the left in Figure 1 to compress the spring 22. In moving the plunger 55 against the spring the plunger hook 28 hits an-

other nose 42 on the locking lever 20 thereby tipping the latter anticlockwise on the pivot 30. Thus the long arm 31 is raised and the hook 33 snaps up past the armature lever hook 32 and comes to rest thereupon by gravity, the plunger at the same time being pushed slightly to the right in Fig. 1 but being locked against movement in either direction by the locking lever nose 29. When now the magnet is energized due to the closing of the circuit at 14—15, Fig. 4, the armature lever hook 32 moves away from the locking lever hook 33, the locking lever falls down and the plunger is released. The spring then pushes the plunger to the right in Fig. 1 to operate the stop handle. The spring 22 is very strong so the plunger moves very quickly and the hook 28 would strike the wall of the box with a blow. However a cushion spring 44 takes the blow by the hook 28. When the locking lever drops the circuit is broken at 18, the magnet is deenergized, and the spring 35 moves the armature lever into position as shown ready to catch the hook 33 of the locking lever when the release is reset by the operator.

This releasing device is extremely simple to construct and assemble. After the armature lever and magnet are mounted, the locking lever is easily inserted to catch the contact 18, the pivot 30 being put in from the outside. Then the plunger is dropped into the slot 24, the cover put on and the device is then ready for installation and operation. Heretofore, so far as I know, such releases have had a plurality of levers for various purposes interposed between the armature lever and the plunger. This device uses only one lever 20. The release is readily prepared for driving units having different

throws of the stop handle by merely lifting out the plunger, removing a pin 50, Fig. 3 to detach the hook 28 by a sliding movement and putting another hook on having a length whereby the movement of the plunger to the right in Fig. 1 will be of a length to correspond with the movement of the stop handle. The longer the hook 28 the sooner it hits the cushioning spring 44 and the shorter is the plunger movement and vice versa.

I claim:

In an electric release for knitting machines wherein is provided an electric circuit with a normally open circuit closer controlled by a travelling thread and which includes a stop handle; a plunger for actuating said stop handle, a hook on said plunger, a spring for moving the plunger in one direction, a gravity actuated plunger locking lever, two noses thereon, one of said noses engaging said plunger hook to hold the plunger immovable against the action of said spring, an electromagnet in said circuit, an armature lever for said magnet, interengaging cooperating means on said locking lever and on said armature lever for holding said locking lever nose in engagement with said plunger, the second nose on said locking lever engageable by said plunger hook to move the locking lever from a gravity actuated position into plunger holding position by said first named nose, said interengaging means on the locking and armature levers being disengaged when the armature lever is attracted by the magnet whereby to cause the locking lever to become gravity operated to release the said plunger for action by said spring.

DAVID WACHSMAN.
